TRANSMISSION LINKAGE FOR GRADING MACHINES

Herbert W. Carnes, Swampscott, and Charles C. Thomas, West Medford, Mass., assignors to North American Research Corporation, Cambridge, Mass., a corporation of Massachusetts

Application August 26, 1946, Serial No. 692,960

6 Claims. (Cl. 33—147)

1

This invention relates to grading machines of the general type known as Nichols, Cogswell and Johnston machines for grading leather blanks, such as soles, heel lifts, counters, and other blanks of a similar nature.

The principal object of the invention is to reduce friction in and generally improve the efficiency of machines of the type herein described and referred to.

Another object is to reduce wear in the journal boxes of the detecting roll and adjacent parts which directly affects the smoothness and accuracy of the grading.

Still another object is to eliminate certain bending stresses now present in the spring which provides a yielding connection between the supporting yoke of the movable detector roll and the transmission lever, so as to maintain at all times a purely axial load on said spring.

Other objects and novel features will be more apparent as the description of the construction and operation of the invention progresses.

The mechanism about to be described is adapted for use in many of the Nichols, Cogswell and Johnston grading machines now in operation, and requires only slight alteration of the machines for installation.

In the interest of reducing duplication and repetitions, the invention is illustrated as applied to the machine disclosed in Patent No. 1,743,320, dated January 14, 1930, to Leander A. Cogswell. This machine is typical of those now in use for which the present invention is primarily adapted. Only those parts of the machine which are essential to the understanding of the present invention are shown. In the drawings,

Fig. 1 is a fragmentary central elevation of Fig. 5 of the said Cogswell patent, particularly showing the improvement in the connecting linkage between the floating detector roll and the transmission lever, and

Fig. 2 is a cross-section taken on line 2—2 of Fig. 1 corresponding to Fig. 6 of the above-mentioned Cogswell patent but looking toward the front of the machine.

Referring more in detail to the drawings, the blanks are fed into the machine from a table 10, between guides 12, the nearest of which is not shown in Fig. 1, to the feed rolls 13 and 14. The upper roll 13 is mounted in journal boxes 15—15 which are held stationary during the operation of the machine but are vertically adjustable in slide-ways on the machine frame by means of screws 16—16, worm gears 17—17, and worms 18—18 on hand shaft 19. The shaft of lower or detector roll 14, sometimes referred to as a feeler roll, is mounted in journal boxes 100—100, which slide in the same ways on the frame as the upper journal boxes 15—15. Journal boxes 100—100 are fastened to yoke 130. Spring 110, acting through

2

levers 120—120 and yoke 130, yieldingly urges detector roll 14 toward stationary roll 13, substantially as shown in the Cogswell patent herein referred to.

The rolls 13 and 14 feed the blank forward between a continuously travelling chain 140 and a yielding, spring pressed shoe 150, which presses the blank down firmly into engagement with the chain so that the latter will continue to carry the blank forward after it leaves the rolls 13 and 14 and present it to the skiving mechanism (not shown) which skives the blank to the minimum thickness as detected by the roll 14.

The up and down motion of the detector roll 14 in response to the varying thickness of a blank is transmitted to a rock-lever 190 hereinafter referred to as the transmission lever. The linkage from the detector roll 14 to the transmission lever 190 comprises the universal connecting rods 20 and spring assembly which is the subject matter of this invention.

Referring first to Figs. 6 and 7 of the Cogswell patent cited herein and using the reference numerals there shown, it can be seen that transmission lever 19 is there connected to yoke 13 by means of rods 20 which are secured to the yoke by pin joints and extend through holes in lever 19 where their ends are held in place by nuts and washers. Even the slight rotation of lever 19 about shaft 22 which results from passage of a blank through the rolls is sufficient to cause binding in the pin joints, which interferes with the tilting of detector roll 4 to accommodate blanks of uneven thickness. A twist is likewise transmitted through yoke 13 to journal boxes 10, resulting in excessive friction and considerable wear in the slideways and journal boxes. Considerable bending stress is also developed in the rods. In addition spring 21, which rests against the underside of yoke 13 and serves to press lever 19 against the washers on rods 20, is subject to bending due to rotation of lever 19. The alteration in spring characteristics thereby resulting adversely affects the accuracy of the grading. To eliminate these difficulties the connecting rod and spring assembly shown in the Cogswell patent has been replaced with the present invention on machines of this and similar types.

Referring now to Figs. 1 and 2 herein, yoke 130 and transmission lever 190 corresponding to yoke 13 and lever 19 in Cogswell are connected by rods 200 having hemispherical upper ends 201, which rest in appropriate sockets in the yoke. The lower ends of the rods 200 are provided with adjustment ball nuts 202 operating in appropriate sockets on the lower side of the transmission lever 190 better shown in Fig. 2. It is evident that free universal movement of rods 200 is thus provided with respect to both the yoke 130 and transmission lever 190. Twisting of journal boxes

100—100 in their respective slide ways, with the resulting friction and wear, is therefore eliminated.

It is apparent that rods 200 serve to restrain lever 190 in the downward direction only. To provide yielding restraint of the lever in the upward direction, a novel spring arrangement is provided. A projection 315 on the under side of lever 190 accommodates a deep recess, and an opening 320, which is adapted to form a socket for hemispherical member 325. Rod 310, the upper end of which is rounded and seats in conical recess 300 on the underside of yoke 130, slides loosely in member 325. Spring 210 engages the flat side of the hemispherical member 325 and is adjusted to the proper tension by means of a washer and retaining nut 330 which is threaded on rod 310. Since universal movement is provided for rod 310 with respect to yoke 130 and member 325 with respect to lever 190, the rod and hemispherical member 325 tend to adjust their respective positions so as to maintain the load on spring 315 purely axial regardless of the position assumed by yoke 130 and lever 190.

It must be borne in mind that the object of the grading operation is to determine the thickness of the thinnest portion of the blank and transmit this value to an indicating or skiving device so that the entire blank may be cut down to a corresponding uniform thickness. In the said Cogswell machine, a ratchet and pawl mechanism is put into operation when a blank enters the grading rolls, so as to lock the transmission lever against downward travel. The upward movement of the transmission lever is governed by the position of the movable detector roll, and it is apparent that the highest position assumed by the lever corresponds to the minimum thickness encountered by the rolls during passage of a blank. Because of the binding of the connecting rod arrangement shown in the Cogswell patent, the lower detecting roll is frequently prevented from tilting freely when a blank of tapered cross section is encountered, with the result that the true minimum thickness is not transmitted. With the arrangement disclosed herein, the separable universal joints on both top and bottom of the connecting rods allow the detector roll to tilt freely, raising lever 190 by means of either rod to a position corresponding to the thickness of the thinner side of a tapered blank. It is evident that the new arrangement herein disclosed, by freeing the motion of the detector roll, greatly improves the accuracy and efficiency of the machine with a considerable reduction in the percentage of rejects among the blanks after the skiving operation.

Since certain changes may be made in the above-described article and different embodiments of the invention could be made without departing from the scope thereof, it is intended that all matter contained in the above description or shown in the accompanying drawing shall be interpreted as illustrative only and not in a limiting sense.

We claim:

1. In a grading machine of the class described having detecting means, including a floating roll, for detecting the thickness of material, and a transmission lever adapted to transmit the minimum thickness so detected to other mechanism; a linkage arranged to limit the separation of said roll and said lever and universally movable

with respect to both; and means comprising a compression spring universally seated on said lever and a compression rod universally pivoted with respect to said roll for normally holding said roll and said lever apart to the limit permitted by said linkage.

2. Apparatus according to claim 1 wherein said linkage comprises connecting rods having ball and socket joints at both ends.

3. In a grading machine of the class described having detecting means, including a floating roll, for detecting the thickness of material, and a transmission lever adapted to transmit the minimum thickness so detected to other mechanisms; a linkage arranged to limit the separation of said roll and said lever, said linkage comprising a connecting rod having ball and socket joints at both ends; and a spring universally mounted on said lever and arranged to urge said roll and said lever apart to the limit permitted by said linkage.

4. In a grading machine of the class described having detecting means, including a floating roll, for detecting the thickness of material, and a transmission lever adapted to transmit the minimum thickness so detected to other mechanisms, and having a recess; a yoke supporting said roll, said yoke having a conical recess; a linkage arranged to limit the separation of said yoke and said lever; a compression rod having a rounded end which is seated in said conical recess, and carrying a projecting shoulder; a hemispherical ball member seated in the recess in said lever; and a coil spring having one end engaged with said shoulder and the other end pressing against the flat side of said ball member for normally holding said roll and said lever apart to the limit permitted by said linkage.

5. Apparatus according to claim 4 wherein said linkage comprises connecting rods having ball and socket joints at both ends.

6. In a grading machine of the class described having detecting means, including a floating roll, for detecting the thickness of material, and a transmission lever adapted to transmit the minimum thickness so detected to other mechanisms, and having a recess; a yoke supporting said roll, said yoke having a conical recess; a linkage arranged to limit the separation of said yoke and said lever and universally connected to both; a compression rod having a rounded end which is seated in said conical recess, and carrying a projecting shoulder; a hemispherical ball member seated in the recess in said lever; and a coil spring having one end engaged with said shoulder and the other end pressing against the flat side of said ball member for normally holding said roll and said lever apart to the limit permitted by said linkage.
